Design for Cooking Stove

Res. 568

Anthony J. Gallagher, and
John J. Baker, of Philadelphia, Pa.
Letters Patent No. 568 - Dated May 31st 1853.

mmmm

The schedule referred to in these Letters Patent and making part of the same

mmmmmm

To all whom it may concern:

Be it known that we, Anthony J. Gallagher and John J. Baker, trading under the firm of Gallagher & Baker of the City of Philadelphia, in the

178

Wes. 568

County of Philadelphia, and State of Pennsylvania, have invented or produced a new and original design which they have applied to a Cooking Stove named the Morning Star and we do hereby declare that the following is a full and exact description of the same-

Fig: 1. is a side elevation of the stove with its ornaments,

" 2, is the upper front of the stove with its name and ornaments.

" 3, is the lower front of the stove with its name and ornaments.

Letter A, Fig 1, is the ornaments of the baking oven door-

Letter B, Fig 1, is the ornaments of the fire box door-

Letter C, Fig 1, is the ornaments of the side of the Roasting oven

Letter E, Fig 1, is the ornament around the bottom of the stove -

Letter D, Fig 2, is the ornament or border around the stove bottom

Letter F, Fig 3, is the ornament on the lower front of the stove -

What we claim as our invention or production and wish to secure by Letters Patent, is the design and configuration of the ornaments for a Cooking stove as above described and shown in the accompanying drawings.
